United States Patent Office.

PELEG WERNI AND REUBEN B. DE BARE, OF CHICAGO, ILLINOIS, ASSIGNORS
TO REUBEN B. DE BARE, OF THE SAME PLACE.

Letters Patent No. 71,669, dated December 3, 1867.

IMPROVEMENT IN SAWING-MACHINES.

The Schedule referred to in these Letters Patent and making part of the same.

TO ALL WHOM IT MAY CONCERN:

Be it known that we, PELEG WERNI and REUBEN B. DE BARE, of Chicago, in the county of Cook, and State of Illinois, have invented a new and useful Improvement in Machines for Sawing Wood; and we do hereby declare and make known that the following is a full, clear, and exact description of the same, reference being had to the accompanying drawings, and the figures and letters of reference marked thereon, which form part of this specification.

To enable those skilled in the art to understand how to construct and use our invention, we will proceed to describe the same with particularity, making reference in so doing to the aforesaid drawings, in which—

Figure 1 represents a plan or top view of our invention, and

Figure 2 a side elevation of the same.

Similar letters of reference in the several figures denote the same parts of our invention.

A represents a suitable frame, supported upon any suitable supports, B B, and provided with an upright frame, C, upon and within which the saw is operated, as hereinafter described. D represents a support, upon which the stick of wood is placed to be sawed, n n being pins, or their equivalent, to hold the same firmly in place. E represents a horizontal shaft, having its bearings upon the frame, and is provided with a balance-wheel, F, and a crank, H, whereby the same may be revolved by hand, or said shaft may be revolved in any other suitable manner. Upon said shaft is fixed a pinion, marked G, having the ordinary cogs g upon one-half of its circumference, and having the remainder of its circumference smooth, as indicated in the drawings. This pinion is arranged within a double rack, marked J, as shown, and by reason of the aforesaid peculiar construction of the pinion G, the continuous revolution of the shaft E and pinion G in one direction will impart a reciprocating motion to the rack, and consequently to the saw, N, whose frame, M, is attached to the said reciprocating rack by means of the removable pins e e passing through the shank K of the rack and the handle L of the saw-frame. R represents a rod, provided with a nut, P, by means of which the saw may be adjusted at the proper tension in its frame. a a represent two vertical rods, attached to the upright frame C, having a slide, T, thereupon, which moves freely up and down the same, and through which slide the rod R of the saw-frame passes, and is held in the proper position when the machine is in operation. A cord, b, is attached to said slide T, and passes over a pulley, c, at the top of the upright frame C, and thence down to be attached to a pin, h, on the frame. Said cord is also provided with a loop, d, which may be drawn up and hitched over a pin, m, to hold the saw up while the stick or log is being adjusted upon the holder D, before mentioned. When the wood is in the proper position, the loop D is released, and the weight of the saw rests upon the wood being sawed, while the machine is operated as before described.

The power or balance-wheel F is removable from its shaft, when desired, and may be arranged upon a suitable shaft, supported in bearings s in the front of the machine, so that by raising up the rear of the same it may be readily moved from place to place like a wheel-barrow.

We are aware that a double rack and pinion, similar to the one used in our machine, has been used for other purposes, and also that a reciprocating saw, suspended in supports having a vertical adjustment, has been heretofore used; we do not therefore claim broadly any of the points aforesaid, but simply our specific arrangement.

Having described the construction and operation of our invention, we will specify what we claim, and desire to secure by Letters Patent:

We claim suspending the saw upon the rod R, passing through a slide, T, which has a vertical movement upon rods a a, attached to the vertical frame, said slide being provided with a cord, b, passing over a pulley, c, all constructed and operating in the manner as and for the purposes specified.

P. WERNI,
R. B. DE BARE.
